CLAIM

I claim the ornamental design for a vending machine, as substantially shown and described.

DESCRIPTION

FIG. 1 is a perspective view of a vending machine of the present invention.

FIG. 2 is a front view of the vending machine of the present invention.

FIG. 3 is a rear view of the vending machine of the present invention.

FIG. 4 is a right side view of the vending machine of the present invention.

FIG. 5 is a left side view of the vending machine of the present invention.

FIG. 6 is a top plan view of the vending machine of the present invention; and,

FIG. 7 is a bottom plan view of the vending machine of the present invention.

The broken lines illustrate the environment of the design and portions of the vending machine that form no part of the claimed design.
